HENRY KRATZ, OF BALTIMORE, MARYLAND, ASSIGNOR TO CONTINENTAL CAN COMPANY, INC., OF NEW YORK, N. Y., A CORPORATION OF NEW YORK

SHEET FEEDING DEVICE

Application filed October 28, 1931. Serial No. 570,692.

The invention relates to new and useful improvements in sheet feeding devices, and more particularly to devices for feeding metal sheets one at a time from a stack or pile.

An object of the invention is to provide a sheet feeding mechanism with a sheet separating device which engages the forward edge portion of the sheet, retracts and lifts the same for freeing said sheet from the sheets beneath prior to the feeding of the sheet.

A further object of the invention is to provide a sheet separating device of the above type with means for vibrating the same after the sheet has been lifted from the stack for insuring the release of the suction lift of said sheet on the underlying sheet.

These and other objects will in part be obvious and will in part be hereinafter more fully disclosed.

In the drawings which show by way of illustration one embodiment of the invention—

Figure 1 is a side view of a portion of a sheet feeding mechanism embodying the improvements;

Fig. 2 is a plan view of a portion of the machine to which the improvements are applied;

Fig. 3 is a view partly in section and partly in side elevation showing the sheet lifting mechanism, the feeding mechanism and the separating mechanism;

Fig. 4 is a detail showing the sheet separating device and the cam for operating the same;

Fig. 5 is a detail showing the control valve and the suction pipes leading therefrom to the lifting cups and the separating cup;

Fig. 6 is a detail in vertical section of the separating cup, and

Fig. 7 is a diagrammatic view showing the sheet retracted and lifted so as to unlock it from a hook on the underlying sheet.

The invention is shown as applied to an automatic stack lifting and sheet feeding device such as disclosed in the patent to Henry A. Fink #1,695,233, granted December 11, 1928. In the operation of this sheet

feeding mechanism, the rear portion of the topmost sheet is lifted by suction cups into the path of reciprocation of a feed finger which engages the rear edge of the sheet and feeds the sheet forward into the machine. The machine is particularly adapted for use in connection with a sheet slitter, but it may be used for other purposes. It sometimes occurs that in handling stacked sheets, the edges of the sheets become bruised, forming hooks which so lock two sheets together, that one will carry the other along when it is fed from the stack. The present invention has to do with a sheet separating device which works in conjunction with the sheet lifting and feeding mechanism, as shown in this Fink patent. This sheet separating device is in the form of a suction cup carried by a swinging lever operated by a cam so that the cup is moved down into contact with the sheet adjacent the forward edge thereof, and when this suction cup is raised, it will cause the sheet to buckle and be retracted so as to unlock the same from any hook formed on the underlying sheet.

The separating device after it reaches the upper end of its movement and has freed the sheet from the underlying sheet, is given a vibration for the purpose of breaking any suction lift between the raised sheet and the underlying sheet, thus insuring that the front edge portion of only one sheet is lifted. After the sheet has been thus separated, the suction cups adjacent the rear edge of the sheet will raise said portion so that the feeding device will engage said rear portion and convey the sheet away from the stack and into the mechanism which is to operate on the sheet. The suction cups are controlled by a valve which is so timed as to bring about the lifting of the sheet in the manner described and the releasing of the sheet for the feed finger to move the same forward.

The invention will be better understood by a detail description of the present illustrated embodiment thereof. The machine in general includes a main frame 1 on which is mounted a sheet supporting device 2. The stacked sheets are indicated diagrammatically at S in Fig. 1 of the drawings. This

stack lifting and feeding mechanism is shown as used in connection with a slitter, the frame of which is indicated in broken lines at 3. The sheet lifting mechanism is provided with 5 automatic means for maintaining the top of the stack at a predetermined level, that is, on a level with the table or support 4 over which the sheets are fed into the slitter. The sheets are lifted from the stack by suction 10 cups 5, 5, only one of which is shown in the drawings. The suction cup is carried by a rod 6 which is attached to a slide 7 carrying a roller 8 bearing on a lift cam 9. There are two lift cams, one for each suction cup. These 15 lift cams are mounted on a shaft 10 which is rotated by suitable driving mechanism. Each suction cup 5 is connected to a pipe 11. These pipes are in turn connected to a control valve 12 which controls the suction 20 on the cup 5. The valve is so timed as to place a suction on the cup for the lifting of the sheet, and the sheet is released from the suction cup when the feeding device has been positioned so as to raise the sheet. The lift 25 cams for the suction cups 5 are shaped as clearly shown in the drawings so as to lift the cups quickly, holding the cup in raised position for a short time to enable the sheet to be fed from underneath the cup, after 30 which it is lowered on to the stack. The lift cam is provided with a short radially extended portion 9^a which gives a slight lift to the suction cup, releasing the same for the purpose of lifting the sheet to break the 35 suction grip between the topmost sheet and the underlying sheet. The sheets are fed from the stack by a feeding device in the form of a feed finger 13. This feeding finger 13 is carried by a crosshead 14 which is mounted 40 for reciprocation on a supporting rail 15. The crosshead 14 has depending lugs 16 between which is placed a link 17 which is pivoted to the lugs by a pivot pin 18. The finger 13 is mounted on the link 17, and thus 45 is supported by the crosshead 14. The other end of the link 17 is pivoted at 19 to a swinging arm 20. The arm 20 is pivoted at 21 to a bracket 22 carried by the frame of the machine. An eccentric strap 23 is 50 pivoted at 24 to the arm 20, and cooperates with an eccentric 25 on the shaft 10. As the shaft 10 rotates, the eccentric will oscillate the arm 20 and this causes the crosshead 14 to move back and forth from the full line 55 position shown in Fig. 3 to the broken line position shown therein. This is the length of feed stroke of the finger, and by this movement the sheet is fed forward so as to be engaged by a conveying device which conveys the sheet through the mechanism operating upon the same.

Mounted on a bracket 26 is a presser foot member 27. There are two presser feet which are located at opposite sides of the suction 65 cups and the feeding device. The suction

cups are comparatively close to the feeding device, and the purpose of these presser feet is to cause the sheet to be buckled at the center thereof for the purpose of releasing any suction grip of the sheet on the underlying sheet. This insures that only one sheet will be lifted by the suction cups and placed in position for the feeding device to move the sheet forward.

The machine thus referred to is substantially the same as shown and described in the Fink patent, and further detail description thereof is not thought necessary.

It often occurs during the handling of a stack of sheets that the edges will be knocked and bruised so as to turn the edge on the sheet forming a hook so that it is locked to the sheet next above. In such cases, when a sheet is fed from the stack, it carries along with it the underlying sheet, thus feeding two sheets at a time into the operating mechanism, which injures the sheets or the parts of the machine operating thereon. The present invention, as noted above, is directed to a means for unlocking any hooked edges so as to insure the feeding of only one sheet at a time. This is accomplished by the separating mechanism which separates the uppermost sheet from the next sheet underlying the same. This separating mechanism includes a suction cup 28 which is preferably larger in diameter than the suction cup 5. The suction cup is shown in detail in Fig. 6, and includes a rubber cup secured to a shank 29 which is pivoted at 30 to a lever 31. Said lever 31 has a series of openings 32 therein, so that the pivot pin supporting the cup may be shifted from one position to another for different widths of sheets. The suction cup is placed under vacuum by a flexible pipe 34 leading to the valve 12. The valve 12 is timed so as to create a suction within the cup 28, so as to cause said cup to grip a sheet when pressed against the same and lift the sheet with the cup. The lever 31, as clearly shown in Fig. 3 of the drawings, is pivoted at 35 to a bracket arm 36 attached to the frame of the machine. Said lever 31 carries a roller 37 bearing against a cam 38 on the shaft 10. The cam 38 is provided with a concentric portion 39, a cutaway radial portion 40 and a cam radial portion 41. There is also formed in the concentric portion 39 a series of reverse curved sections 42, 42. The cam 38 turns in the direction of the arrow as shown in Fig. 3. When the cam is in the position shown in this figure, the cup is in its lowered position and is in contact with the sheet. It will grip the sheet firmly, so that when the cup is raised, the sheet will be lifted therewith. The pivotal point 30 between the lever and the cup is at a considerable distance below the fulcrum point 35 where the lever is supported, and therefore, as the lever is depressed at the left-hand end in Fig. 3, it will be raised

at the right-hand end, and the pivotal point 30 will move away from the fulcrum point 35 to a slight extent. The cup, however, being pivoted to the lever, will swing inward, and the resulting action is a buckling of the sheet, as shown in Fig. 7. The sheet is not only buckled, but is retracted at the advance edge thereof, indicated at *a* in the drawings, and this operates to release said advance edge 10 from the hook on the advance edge of the underlying sheet, which is indicated at *b*. When the cup, which is lifted quickly, reaches the upper end of its stroke, it remains in the raised position as the cam 38 continues to rotate, and as the roller passes over the curves or depressions 42, the cup will be vibrated up and down, and this will tend to shake loose any sheet clinging to the under face of the uppermost sheet, due to the suction lift of 20 vacuum pockets in the sheet.

In the operation of the machine, the separating device engages the topmost sheet, un-hooks the ends, if they are interlocked, and lifts the forward or advance edge of the sheet, 25 shaking it loose from the under sheet, and while this is taking place, the suction cups 5 are in contact with the sheet, holding the sheet down on the stack. When the surface 9 of the cam 9 contacts with the roller 8, it 30 will then lift the suction cups 5 and the sheet will be raised into position for the feed finger 13 to engage the rear edge of the sheet and move it forward into the mechanism which operates upon the sheet. The cam 38 lifts 35 the suction cup 28, and the spring 43 holds the lever 34 in contact with the cam and forces the cup downward into contact with the sheets as the control cam releases the same. When the suction is released on the cup 28, 40 then the sheet will be released and it will straighten out. This occurs practically simultaneously with the release of the sheet from the suction cups 5, preliminary to the feeding of the sheet by the forward movement of the feed finger, and therefore, the sheet will be fed from the stack without again being hooked so as to carry with it the underlying sheet.

While the sheet separating device is shown 45 as used in connection with the automatic stack raising mechanism and sheet feeding device of the Fink patent, it will be understood, of course, that it is adapted for use with other types of stack raising and sheet feeding devices. It will also be understood that the 50 details of construction and the arrangement of the parts may be varied without departing from the spirit of the invention as set forth in the appended claims.

Having thus described the invention, what I claim as new and desire to secure by Letters Patent, is—

1. A sheet feeding mechanism comprising a support for the stacked sheets, a reciprocating feeding device engaging the rear edge

of the sheet for feeding the same from the stack, means for lifting the rear portion of the topmost sheet from the stack for permitting the engagement of the feeding device therewith, and means adapted to engage the topmost sheet adjacent the forward edge thereof for retracting and lifting the forward edge portion of said sheet for freeing the same from the stacked sheets prior to the engagement of the feeding device with the sheet for the movement of the same from the stack.

2. A sheet feeding mechanism comprising a support for the stacked sheets, a reciprocating feeding device engaging the rear edge of the sheet for feeding the same from the stack, means for lifting the rear portion of the topmost sheet from the stack for permitting the engagement of the feeding device therewith, 70 a suction cup adapted to engage the topmost sheet adjacent the forward edge thereof, and means operating to raise the suction cup and tilt the same so as to retract and lift the forward edge portion of the sheet for freeing the same from the stacked sheets prior to the engagement of the feeding device with the sheet for the movement of the same from the stack.

3. A sheet feeding mechanism comprising a support for stacked sheets, a feeding device 95 engaging the rear edge of the sheet for feeding the same from the stack, means for lifting the rear portion of a sheet from the stack for engagement by the feeding device, a lever pivotally supported for oscillation on an axis in rear of the advance edge of the sheet, a suction cup pivoted to the end of the lever and adapted to engage the topmost sheet adjacent its front edge, and a cam for oscillating said lever for retracting and lifting the forward edge of the sheet prior to the lifting of the rear portion of the sheet for engagement by the feeding device.

4. A sheet feeding mechanism comprising 100 a support for stacked sheets, a feeding device engaging the rear edge of the sheet for feeding the same from the stack, means for lifting the rear portion of a sheet from the stack for engagement by the feeding device, a lever pivotally supported for oscillation on an axis 110 in rear of the advance edge of the sheet, a suction cup pivoted to the end of the lever and adapted to engage the topmost sheet adjacent its front edge, a cam for oscillating said lever for retracting and lifting the forward edge of the sheet prior to the lifting of the rear portion of the sheet for engagement by the feeding device, and means whereby said suction cup may be adjusted to different set positions relative to the forward end of the lever.

5. A sheet feeding mechanism comprising a support for stacked sheets, a feeding device 120 engaging the rear edge of the sheet for feeding the same from the stack, means for lift-

- ing the rear portion of a sheet from the stack for engagement by the feeding device, a lever pivotally supported for oscillation on an axis in rear of the advance edge of the sheet, a suction cup pivoted to the end of the lever and adapted to engage the topmost sheet adjacent its front edge, a cam for oscillating said lever for lifting the cup, and a spring for oscillating the lever under control of the cam for lowering the cup, whereby the sheet engaged by the cup is retracted and lifted prior to the lifting of the rear portion of the sheet for engagement by the feeding device.
- 15 6. A sheet feeding mechanism comprising a support for stacked sheets, a feeding device engaging the rear edge of the sheet for feeding the same from the stack, means for lifting the rear portion of a sheet from the stack for engagement by the feeding device, a suction cup adapted to engage a sheet adjacent the forward edge thereof, and means for raising said suction cup and tilting the same so as to retract and lift the forward edge of
- 20 the sheet prior to the lifting of the rear portion of the sheet for engagement by the feeding device, said suction cup raising means operating to vibrate the cup up and down when said cup is at the upper end of its movement.
- 25 7. A sheet feeding mechanism comprising a support for stacked sheets, a feeding device engaging the rear edge of the sheet for feeding the same from the stack, means for lifting the rear portion of a sheet from the stack for engagement by the feeding device, a lever pivotally supported for oscillation on an axis in rear of the advance edge of the sheet, a suction cup pivoted to the end of the lever
- 30 and adapted to engage the topmost sheet adjacent its front edge, a control cam for oscillating said lever, and a spring for holding the lever in contact with the cam, said cam being shaped so as to raise the suction cup
- 35 and so as to vibrate the suction cup when in raised position and gripping the sheet for releasing said lifted sheet from the underlying sheet.

40 In testimony whereof, I affix my signature.
50 HENRY KRATZ.
